UNITED STATES PATENT OFFICE

2,557,459

APPARATUS FOR FEEDING RADIATOR
VAPOR COMBINED WITH AN ANTI-
CORROSION AND ALKALINE INHIBIT-
ING SOLUTION INTO THE FUEL FEED
LINE OF AN INTERNAL-COMBUSTION
ENGINE

Rudolph Oros, Los Angeles, Calif.

Application September 6, 1949, Serial No. 114,234

8 Claims. (Cl. 123—25)

1

This invention has for its primary object to provide a simply constructed apparatus, which as an attachment, may be readily installed on a water cooled internal combustion engine for feeding, into the fuel line thereof, vapor from the radiator combined with a solution for inhibiting corrosion, rust and alkaline deposits, whereby the vapor will improve the combustion of and conserve fuel, and the solution will prevent objectionable and damaging corrosion, rust and alkaline deposits which, due to the water vapor, might otherwise be caused within the cylinders and on the valves, valve seats and other working parts exposed to such vapor.

Another object is to provide apparatus of the character described in which the vapor feed line is installed so as to lead from the tank of the engine radiator, above the water line, to the air intake conduit of the carburetor, for introducing vapor with the carbureted fuel into the engine cylinders, there being a reservoir for the anti-corrosion and alkaline and rust inhibiting solution connected to said vapor feed line whereby the solution is fed with the vapor into the carburetor and thence into the engine.

Another object is to provide apparatus of the character described in which a single valve operable, for example, on the instrument panel of the automobile, is arranged to control the flow of the vapor-solution mixture into the air intake conduit of the carburetor.

Another object is to provide apparatus such as described in which a valved outlet is arranged to regulate the rate of flow of the alkaline and corrosion inhibiting solution into the vapor feed line leading to the air intake of the carburetor and wherein feed of such solution through said outlet is caused by vibration of the reservoir for such solution plus the suction effect in the vapor feed line.

A further object is to provide vapor feed apparatus such as described wherein the overflow drain pipe of the radiator is screened to prevent dust and other foreign matter from being sucked through said pipe into the radiator tank and thence in the vapor feed line leading to the carburetor.

With the foregoing objects in view, together with such other objects and advantages as may subsequently appear, the invention resides in the parts and in the combination, construction and arrangement of parts hereinafter described and claimed, and illustrated by way of example in the accompanying drawing, in which:

Fig. 1 is a fragmentary elevational view of a liquid cooled internal combustion engine as in an automobile showing an apparatus embodying my invention as installed thereon, and

Fig. 2 is a fragmentary sectional view taken on the line 2—2 of Fig. 1 showing the valved outlet for the reservoir for the solution for in-

2

hibiting corrosion and alkaline deposits and the manner of connecting the outlet with the vapor feed lines.

As shown in the accompanying drawing one embodiment of my invention includes the provision of a vapor feed tube or line 3 which is connected with tank 4 of the radiator 5 of a water cooled internal combustion engine 6, here shown as the engine of a motor vehicle having an instrument panel 7. This line is connected with the top of the tank above the water line and leads downwardly to a point of connection 8 with the air intake conduit 9 of the carburetor 10 so that vapor rather than water is conducted to the carburetor and then with the carbureted fuel mixture through the intake manifold 11 to the engine 6. The exclusion of water from the line 3 is further prevented by the goose neck formation 12 in the end of the line connected to the top of the tank 4.

As a means to prevent the suction created in the vapor feed line 3 from drawing dust and foreign matter into the overflow pipe 13 of the radiator and thence into the vapor feed line, the discharge end of the overflow pipe is covered with a suitable screen 14.

It is now seen that in having vapor from the radiator fed into the carburetor as here provided and introduced as a carbureted fuel mixture into the engine, a better and more efficient combustion takes place and a conservation of fuel is achieved.

As here provided a suitable valve 15 is mounted in the vapor feed line 3 for controlling the flow of vapor into the air intake conduit 9. This valve may as here shown be controlled from the instrument panel 7 by means of a suitable Bowden wire unit 16 whereby the driver of the vehicle may start and stop and regulate the flow of vapor at will.

In accordance with this invention, to prevent corrosion, rust and alkaline deposits in the engine due to the introduction of the radiator vapor, I provide for introducing into the vapor feed line 3, a solution for inhibiting corrosion, rust and alkaline deposits. To this end a reservoir 17 is mounted in any suitable manner over or on the engine so that it may be connected with the vapor feed line 3 between the valve 15 and the radiator tank 4 for a gravitational discharge of the aforesaid solution into the feed line, with the valve 15 controlling the flow of the solution as well as the vapor. Accordingly the reservoir is connected to the line 3 by means of a suitable fitting 18 in which a needle valve 19 controls the flow through a passage 20, extending through the fitting and connecting the interior of the reservoir with the line 3.

Any solution which will inhibit corrosion, rust and alkaline deposits may be used and I have

found that a solution of a liquid compound known as Malco 37 is well suited.

When the valve 15 is opened and the engine 6 in operation the suction in the fuel feed line of the engine is effective to draw vapor from the radiator tank through the vapor line 3 and through the carburetor 10 and manifold 11 into the engine for the purpose of improving combustion and conserving fuel.

At the same time the vapor is being fed to the engine, the solution in the reservoir 17 (the needle valve 19 being opened) feed into the line 3 and is drawn with the vapor into the engine. The adjustment of the needle valve 19 determines the rate of flow of solution, it being noted that but a small amount is required in mixture with the vapor to be effective to inhibit rust, corrosion and alkaline deposits. The vibration of the reservoir due to the operation of the engine plus the suction in line 3 induces a feed of the solution into the line 3.

I may use a small amount of a suitable lubricating oil in the aforesaid solution, for the purpose of lubricating the pistons, piston rings and associated parts of the engine.

One solution which I have found to be most effective consists of five gallons of water mixed with approximately two ounces of the rust and corrosion inhibiting compound and three ounces of a suitable cylinder oil. A small amount of this mixture placed in the reservoir 17 will suffice for the operation of the engine over a long period of time.

It will now be apparent that my apparatus as an attachment is readily applicable to water cooled internal combustion engines, will accomplish the objects and purposes hereinbefore stated in a particularly efficacious manner.

While I have shown and described a specific embodiment of my invention, I do not limit myself to the exact details of construction set forth, and the invention embraces such changes, modifications and equivalents of the parts and their formation and arrangement as come within the purview of the appended claims.

I claim:

1. In apparatus for feeding radiator vapor combined with a rust and corrosion inhibiting solution into the carburetor of a liquid cooled internal combustion engine, a vapor feed line having a goose neck end portion connected with top of the tank of the radiator of the engine and having another end portion connecting with the air intake conduit leading to the carburetor, a reservoir for said solution having a discharge means connected to said vapor feed line and a valve for controlling the flow from said line to said carburetor.

2. In apparatus for feeding vapors from the radiator of a liquid cooled internal combustion engine, a vapor feed pipe for connection between the radiator and the air intake conduit from the carburetor of said engine, a reservoir for a solution for inhibiting rust and corrosion connected with said pipe for discharging the solution into the pipe, and a valve in said pipe for controlling the flow therethrough to said air intake conduit.

3. The combination with a water cooled internal combustion engine unit including a radiator having a top wall, and a carburetor having an air intake conduit, of a pipe line connected to and leading from the radiator top wall to the air intake conduit for the carburetor, for conducting vapor to the carburetor; and means for introducing into said line so as to mix with the vapor conducted to said conduit a solution for inhibiting

rust and corrosion within the cylinders of the engine, said solution including a lubricating oil.

4. The combination with a water cooled internal combustion engine unit, of a pipe line leading from the radiator of the engine to the air intake conduit for the carburetor of the engine, for conducting vapor to the carburetor; a valve in said line for controlling the flow to said air intake conduit, and a reservoir for a rust and corrosion inhibiting solution connected to said line between said valve and said radiator for discharging the solution into the line.

5. The combination with a water cooled internal combustion engine unit, of a pipe line leading from the radiator of the engine to the air intake conduit for the carburetor of the engine, for conducting vapor to the carburetor, a valve in said line for controlling the flow to said air intake conduit, and a reservoir for a rust and corrosion inhibiting solution connected to said line between said valve and said radiator for discharging the solution into the line.

6. The combination with a water cooled internal combustion engine unit, of a pipe line leading from the radiator of the engine to the air intake conduit for the carburetor of the engine, for conducting vapor to the carburetor, a valve in said line for controlling the flow to said air intake conduit, and a reservoir for a rust and corrosion inhibiting solution connected to said line between said valve and said radiator for discharging the solution into the line and valve means controlling the flow of the solution into the line.

7. The method of introducing water vapor from the radiator of an internal combustion engine into the engine cylinders, together with a solution for inhibiting rust and corrosion in the engine; which consists in utilizing the suction action in the atmospheric air intake means for the carburetor of the engine to induce flow of vapor from the radiator through conduit means leading to said air intake means, and adding to said vapor after it leaves the radiator and before it reaches the carburetor air intake means a solution for inhibiting rust and corrosion.

8. In apparatus for feeding vapors from the radiator of a liquid cooled internal combustion engine having a carburetor provided with an air intake conduit and in which the radiator has a top wall and is equipped with a downwardly extending overflow pipe leading from beneath and adjacent to said top wall and terminating in a downwardly opening lower end; an air filter extending over the open lower end of said overflow pipe, a vapor feed pipe connecting with and leading from the top wall of the radiator to and connecting with the air intake conduit of the engine carburetor, a reservoir for a solution for limiting rust and corrosion connected with said pipe for discharging the solution into the pipe, a valve for regulating the delivery of the solution into the pipe from said reservoir, and a valve in said pipe for controlling the flow of vapors and solution from said feed pipe to said air intake conduit.
